UNITED STATES PATENT OFFICE.

FRED B. COREY, OF SCHENECTADY, NEW YORK, ASSIGNOR TO GENERAL ELECTRIC COMPANY, A CORPORATION OF NEW YORK.

AUTOMATIC TRAIN-STOP FOR BLOCK-SIGNAL SYSTEMS.

No. 826,886.

Specification of Letters Patent.

Patented Aug. 14, 1906.

Application filed March 10, 1904. Serial No. 197,500.

To all whom it may concern:

Be it known that I, FRED B. COREY, a citizen of the United States, residing at Schenectady, county of Schenectady, State of New York, have invented certain new and useful Improvements in Automatic Train-Stops for Block-Signal Systems, of which the following is a specification.

My invention relates to block-signal systems; and its object is to provide a novel form of automatic train-stop for use in conjunction with such systems.

Block-signal systems have been installed heretofore in which in addition to the signals an automatic train-stop is employed in conjunction with each signal, the train-stop consisting of an arm placed adjacent to the track and arranged to be raised into a vertical position when the signal is at "danger." A valve is placed on each locomotive or motor-car and connected in the air-brake pipe. The valve is arranged to be engaged by the stop-arm when the stop is in a vertical position. Consequently if a car tries to pass a signal while it is at "danger" the valve is opened, the pressure in the train-pipe is reduced, and the brakes are applied. This provides an absolute stop and prevents the engineer or motorman from running past a signal which is set against him. It is, however, desirable in many instances to allow a train to pass the danger-signal at slow speed, and to accomplish this result it has been proposed to replace the valve by a flexible tube to the end of which is attached a closed glass tube. With this arrangement when the car passes a signal at a very slow speed the flexible tube bends on reaching the stop-arm and allows the glass tube to drag over the end of the stop-arm without breaking; but if the train attempts to pass the stop-arm at a high speed the glass tube is broken, the air-brake pipe is connected to the atmosphere, and the brakes are applied. This arrangement has the disadvantage that it is necessary frequently to replace broken tubes, as the tubes are liable to breakages from various accidental causes.

The object of my invention is to provide a novel form of stop-arm which shall allow a train or car to pass a danger-signal if going at a very slow speed, but which shall automatically apply the brakes if the train or car attempts to pass at a high rate of speed, and which shall accomplish this end without em-

ploying any device which must be broken in operation or which is liable to breakage.

My invention will best be understood by reference to the accompanying drawings, in which—

Figure 1 shows a cross-sectional elevation of a railway provided with a stop-arm arranged in accordance with my invention. Fig. 2 shows a side elevation of the same on an enlarged scale.

In the drawings, A represents an automatic stop-arm which when raised to a vertical position, as shown in the drawings, is arranged to be engaged by a valve V, carried on the car C and connected in the air-brake pipe B. The stop-arm A is mounted on the rod or shaft R, which is connected by the link or lever L to the operating mechanism of the signal S in such manner that when the signal is at the danger position, as shown, the rod R is rotated, raising stop-arm A into a vertical position, as shown. Stop-arm A is formed in two pieces, one piece a being secured rigidly to the rod R. The other piece a' is pivoted to the piece a at a' and is normally held in line with the piece a by the flexible strip or spring F, which is secured to the piece a and which engages the stops f on the piece a'. The spring F is made sufficiently flexible so that if valve V is brought slowly into contact with the member a' flexible strip F will be bent into the position shown in dotted lines, allowing valve V to pass by it without opening. The member a' possesses considerable inertia, however, and if the car C is moving rapidly the inertia of member a' is sufficient to knock valve V open, thus applying the brakes. It is thus evident that the flexible stop-arm which I employ possesses the advantages of the glass-tube arrangement, while eliminating the disadvantageous necessity of frequently replacing broken parts.

I do not desire to limit myself to the particular construction and arrangement of parts here shown, since changes which do not depart from the spirit of my invention and which are within the scope of the appended claims will be obvious to those skilled in the art.

What I claim as new, and desire to secure by Letters Patent of the United States, is—

1. In a block-signal system for railways, a car, a brake-controlling device thereon, a

- signal, and a stop-arm controlled by said signal and adapted to engage said device when said signal is at danger, said stop-arm being adapted to move said device to apply the 5 brakes if the car is moving fast and to be moved by said device if the car is moving slowly.
2. In a block-signal system for railways, a car, air-brakes therefor, a valve adapted 10 when opened to apply said brakes, a signal, and a stop-arm controlled by said signal and adapted to engage said valve when said signal is at danger, said stop-arm being adapted to open said valve if the car is moving fast 15 and to be moved by said valve if the car is moving slowly.
3. In a block-signal system for railways, in combination with a signal, a stop-arm adjacent to the track and adapted to be moved 20 into a position to be engaged by a moving car when said signal is moved to danger, said stop-arm being adapted to yield readily to slowly-applied pressure and to resist a sudden blow.
- 25 4. In a block-signal system for railways, a car, a brake-controlling device thereon, a signal, and a stop-arm controlled by said signal and adapted to engage said device when said signal is at danger, said stop-arm being adapted to yield readily to slowly-applied pressure and to resist a sudden blow.
- 30 5. In a block-signal system for railways, a car, air-brakes thereon, a valve controlling said brakes, a signal, and a stop-arm controlled by said signal and adapted to engage said valve when said signal is at danger, said stop-arm being adapted to yield readily to slowly-applied pressure and to resist a sudden blow.
- 35 6. In a block-signal system for railways, in combination with a signal, a stop-arm controlled thereby and comprising a part rigidly connected to the operating mechanism of the signal, a second part pivotally mounted 40 on the first part, a flexible strip or leaf-spring carried by the first part, and stops carried by the second part adapted to engage said leaf-spring when said second part is moved in either direction.
- 45 50 7. In a block-signal system for railways, a car, a speed-controlling device thereon, a signal, and means controlled by said signal for engaging and moving said device on a fast-moving car when said signal is at danger and adapted to allow a slow-moving car to pass 55 without shifting said device regardless of the position of the signal.
8. In a block-signal system for railways, a car, a brake-controlling device thereon, a signal, and means controlled by said signal for 60 engaging and moving said device to apply the brakes on a fast-moving car when said signal is at danger and adapted to allow a slow-moving car to pass without shifting said device regardless of the position of said signal. 65
9. In a block-signal system for railways, a car, a speed-controlling device thereon, a signal, and operative connections between said signal and said device comprising a part controlled by said signal and a part moving 70 with the car adapted to be engaged by the signal-controlled part when the signal is at danger, one of said parts being arranged with high inertia, whereby said device is moved on a fast-moving car when said signal 75 is at danger but is unaffected on a slow-moving car regardless of the position of said signal.
10. In a block-signal system for railways, a car, a speed-controlling device thereon, a signal, and controlling means comprising a part controlled by said signal and a part moving 80 with the car adapted to strike the signal-controlled part when the signal is at danger, one 85 of said parts being arranged with high inertia whereby its action when said parts strike varies with the velocity of the blow, said speed-controlling device being operatively related to said controlling means whereby said device is moved on a fast-moving car 90 when the signal is at danger but is unaffected on a slowly-moving car regardless of the position of said signal.

In witness whereof I have hereunto set my hand this 8th day of March, 1904.

FRED B. COREY.
